UNITED STATES PATENT OFFICE.

BENEDICT E. WILLETT, OF DAYTON, OHIO.

DISPLAY-RACK.

1,311,305.

specification of Letters Patent. Patented July 29, 1919.

Application filed January 25, 1918. Serial No. 213,663.

To all whom it may concern:

Be it known that I, BENEDICT E. WILLETT, a citizen of the United States, residing at Dayton, in the county of Montgomery and State of Ohio, have invented new and useful Improvements in Display-Racks, of which the following is a specification.

This invention relates to new and useful improvements in display racks.

10 The principal object of my invention is to provide, for use in stores and other places, a simple, durable and adjustable rack for holding boxes, baskets and other receptacles in such a manner that their contents may 15 be prominently displayed and conveniently handled. The rack is so constructed that it will readily receive boxes, baskets and other receptacles, and display them in rows at various levels. For example, the boxes or 20 baskets of one row may be disposed directly above those of another row to conserve space and still permit their contents to be displayed and conveniently handled; or, by adjusting the rack, the rows of baskets or 25 boxes may be disposed in step arrangement for a more prominent display of their contents. The construction, arrangement and assembly of the different parts of the rack 30 conduce to its strength and durability, as well as make it adjustable for use and collapsible for shipment.

The preferred form of embodiment of my invention is illustrated in the accompanying drawings, of which Figure 1 is a perspective view of my improved rack ready 35 for use. And Fig. 2 is a side view of one of the adjustable supports for the receptacle holders.

Throughout the specification and drawings, similar reference characters denote corresponding parts.

Referring to the drawings, my improved display rack rests upon a spider which comprises two runners 11, each of which is made up of two angle irons 22 connected at their ends by a bracket member 3 which receives a roller 4. Each pair of angle irons 22 is arranged to present two oppositely disposed upturned flange portions adapted to receive 50 between them the lower ends of two supporting standards 55. (See Fig. 1.)

The standards 55 are preferably disposed

in alignment with each other, one of each pair being connected between its respective angle irons 22, by a screw 6, near the front 55 roller 4, while its companion standard is connected between said angle irons by a screw 7, near the middle portion of its respective runner 1. (See Fig. 2.) The screws 6 and 7 permit the standards 55 to be moved about 60 them as pivots in either direction for a purpose to be hereinafter described.

To hold them in parallelism at all times, there are pivotally connected to the standards 55 at intervals throughout their length, 65 by means of screws 8, cross pieces 9 which are so arranged as to be in parallel relation with each other and the runners 1 during any inclined position of the standards 55. These cross pieces 9 are preferably employed 70 in pairs, so that one cross piece will be on each side of its respective standard as shown in Fig. 1.

The cross pieces 9 terminate in outwardly extending right-angled ends, to which are 75 connected in front, by means of screw bolts 10, horizontal supporting members 11, while to the rear right-angled ends of the cross pieces 9 there are secured, by means of screw bolts 12, horizontal supporting members 13 80 that are slightly longer than the front horizontal supporting members 11.

Each end of the horizontal supporting members 11 extends a sufficient distance beyond the standards 55, for connection to the 85 outer middle portion of a bowed supporting band 14, the ends of each band terminating in angle portions which are connected, by means of screw bolts 15, to the rear horizontal supporting members 13. Each of 90 the bands 14 is preferably semi-circular as shown in Fig. 1, and forms with its respective portion of the supporting member 13 a support for a basket, box or other receptacle that may be placed upon it with a view to 95 displaying its contents and at the same time permitting the latter to be conveniently handled.

Similarly connected to the supporting members 11 and 13, between the two pairs 100 of standards 55, are bowed members or bands 16, each of the latter being formed similarly to the bowed bands 14. There are preferably six of these bowed bands 16 be-

tween the standards 5 5, and three of the bowed bands 14 beyond each pair of standards. However, this number may be increased or decreased if desired.

5. For the purpose of properly bracing the rack just described, there is pivotally connected between the rear ends of each pair of angle irons 2 2, by means of a screw bolt 17, a pair of inclined bracing members 18 18.
10. The upper ends of the latter straddle their respective standard 5, and are provided with a row of apertures 19, each of which is adapted to receive a screw bolt 20 that passes through a hole in said standard. When it is desired to vary the angle of inclination of the standards 5 5, to place the bowed receptacle holders at a higher or a lower level, said standards are turned about their pivots 6 and 7 until the desired inclination is secured. A screw bolt 20 is then passed through each rear standard 5 from an aperture 19 into a corresponding aperture on the other side of said standard, after which a nut 21 is applied to the outer end of the screw bolts and tightened thereon to hold the standards in their adjusted position. To assist in bracing the rack, a bar 22 is preferably connected between each rear end of the said runners 1 1.
30. My improved rack is so constructed that it may be shipped to the user in sections, which he may readily assemble by reason of the numerous screws and bolts that are employed as mediums for uniting the different parts.

In operation, baskets containing vegetables, fruit or other articles may be readily placed in the bowed holders 14 and 16, or boxes or other receptacles containing like products may be placed on top of them for display. If the space will not permit a step arrangement of the rows of receptacles, the standards 5 5 may be positioned so that they will be perpendicular to the runners 1 1, so as to place the various receptacles in approximate vertical alinement, in which position their contents may be displayed and conveniently handled.

50. However, to more prominently display the contents of the receptacles, where the space will permit, the standards 5 5 may be inclined and held in such positions by the apertured bracing members 18 18, to display the baskets, boxes or other receptacles in step or seat arrangement: that is, with the front portions of the receptacles in one row, in advance of the front portions of the receptacles in the row above.

60. By means of the rollers 4, the rack may be readily moved from one location to another. The angle irons, bracing and other parts impart to it great strength, while its open framework is conducive to sanitation.

Having described my invention, I claim:

65. 1. In a display rack, a pair of horizontal

base members, a pair of parallel standards pivotally secured at their lower ends to each base member, oppositely-disposed cross pieces secured to the sides of said parallel standards at intervals throughout their length, a horizontal supporting member secured to the front and rear ends of each two oppositely-disposed cross pieces, and receptacle holders connected between each two oppositely-disposed horizontal supporting members.

2. In a display rack, a pair of horizontal base members, a pair of parallel standards pivotally secured at their lower ends to each base member, oppositely-disposed cross pieces secured to the sides of said parallel standards at intervals throughout their length, a horizontal supporting member secured to the front and rear ends of each two oppositely-disposed cross pieces, and bowed elements connected between each two oppositely-disposed horizontal supporting members, to receive baskets or other receptacles to prominently display their contents.

3. In a display rack, a pair of horizontal base members, each base member consisting of two angle-irons so connected that two corresponding sides thereof face each other a short distance apart, a pair of parallel standards pivotally secured at their lower ends between the sides of each pair of angle irons that face each other, cross pieces pivotally secured to said standards at intervals throughout their length, horizontal supporting members secured to the ends of said cross pieces, and receptacle holders connected between said horizontal supporting members.

4. In a display rack, a pair of horizontal base members, each base member consisting of two angle-irons so connected that two corresponding sides thereof face each other a short distance apart, a roller at each end of said base members, a pair of parallel standards secured at their lower ends between the facing sides of each pair of angle-irons, a pair of cross pieces straddling the side portions of each pair of standards at intervals throughout their length, the cross pieces of one pair of standards being directly opposite those of the other pair of standards, said cross pieces having right-angled ends, a horizontal supporting member secured to the front and rear right-angled ends of each row of cross pieces, and bowed receptacle holders connected in alinement between the horizontal supporting members belonging to each row of cross pieces.

5. In a display rack, a pair of horizontal base members, a pair of parallel standards pivotally connected at their lower ends to each base member, cross pieces secured to the sides of said parallel standards at intervals throughout their length, a receptacle-

holding frame-work carried by said cross pieces, and inclined bracing members whose lower ends are pivotally connected to the rear portions of said base members, and 5 whose upper ends contain a plurality of apertures in longitudinal alinement to receive an element adapted to be passed

through each rear standard, to adjustably support the receptacle-holding framework.

In testimony whereof I have hereunto set 10 my hand this 22 day of January, 1918.

BENEDICT E. WILLETT.

Witness:

H. S. SMITH.
